UNITED STATES PATENT OFFICE.

WILLIAM A. JAMESON, OF NIAGARA FALLS, NEW YORK.

DESIGN FOR A HANDLE FOR SPOONS, &c.

SPECIFICATION forming part of Design No. 29,324, dated September 13, 1898.

Application filed August 8, 1898. Serial No. 688,114. Term of patent 7 years.

To all whom it may concern:

Be it known that I, WILLIAM A. JAMESON, a citizen of the United States, residing at Niagara Falls, in the county of Niagara and State of New York, have invented and produced a new and original Design for Handles for Spoons, Forks, and Similar Articles, of which the following is a specification, reference being had to the accompanying drawings, forming a part thereof.

This design relates to the ornamentation of spoon and fork handles.

In the accompanying drawings, Figure 1 is a face or front view of a spoon embodying my design. Fig. 2 is a rear view of the same.

The characteristic feature of my design consists of the peculiar ornaments on the obverse and reverse sides of the spoon or fork handle, combined and arranged as shown in the drawings.

The handle has approximately the configuration commonly known as the "fiddle outline." Upon the outer enlargement of the handle and on the front or obverse side there is a plain field flanked by a pair of foliated scrolls *a*, and surmounting these scrolls is a triangular leaf-like ornament *b*. Below the scrolls *a* and extending along the concave edges of the handle area is a pair of curved ribs or bars *c*, and on the inner side of each of these bars is a row of beads *d*, which follows the curvature of the bars. Extending along the edges of the shank or narrow portion of the handle are bars or ribs *e*, and between the adjacent ends of these bars and the curved bars *c* are foliated ornaments *f*. Upon the inner portion of the shank is a leaf-like ornament *g*. On the rear or reverse side of the handle the outer enlargement is edged by fanciful scroll ornaments *h*, and on the

inner sides of these ornaments and arranged concentrically therewith are smaller rococo or scroll-like ornaments *h'*. Upon the tip or tapering portion of the handle, above the large scrolls *h* and extending along the margin 45 thereof, are scalloped or shell ornaments *i*, and in the space between the latter ornaments and the inner scrolls *h* is an inverted heart-shaped ornament *j*. Below the large scrolls *h* and extending along the edges of the 50 handle are foliated or rococo ornaments *k*, and between these ornaments are two downwardly-converging rows of beads *l*.

m are ribs extending along the edges of the shank or contracted inner portion of the handle, and between the flaring upper ends of these ribs and the rococo ornaments *k* are scroll ornaments *n*. Extending downwardly from the lower ends of the scrolls *n* and arranged between the ribs *m* are two downwardly-converging rows of beads *n'*.

My design is obviously applicable to the handle of a fork as well as a spoon-handle.

What I claim is—

1. In the design for the handle of a spoon, 65 fork or similar article, the obverse, substantially as herein shown and described.

2. In the design for the handle of a spoon, fork or similar article, the reverse, substantially as herein shown and described.

3. The design for the handle of a spoon, fork or similar article, substantially as herein shown and described.

Witness my hand this 18th day of June, 1898.

WILLIAM A. JAMESON.
